UNITED STATES PATENT OFFICE

ALBERT B. DEWEY, JR., AND NICHOLAS D. CHERONIS, OF CHICAGO, ILLINOIS; SAID CHERONIS ASSIGNOR TO SAID DEWEY

PRINTED MATTER

No Drawing. Application filed January 30, 1928. Serial No. 250,714.

Our invention relates to printed matter, and includes among its objects and advantages the provision of an improved instrumentality having unusual attention values for circularizing and other uses, by reason of changes that take place in the appearance of it while it is under the observation of the recipient.

According to the invention, we prepare a light-sensitive sheet of paper such as the well-known blue print paper. One such paper may be prepared by treating a paper sheet with a solution containing potassium ferricyanide and ferric ammonium citrate. The addition of a very small amount of a uranium salt such as uranium nitrate will materially accelerate the response of the finished paper.

The finished and unexposed paper may receive indicia printed thereon in ink preferably of a color substantially identical with the blue color the paper will have after exposure to light either with or without subsequent immersion in water.

It may also receive another or alternative set of indicia printed with ink of a color substantially identical with the color of the undeveloped paper, which, in case of the blue print paper described above, will be a pale yellowish white.

Any suitable ink may be employed for this purpose. We prefer a colloidal ink composed primarily of a quick-drying varnish capable of printing in a thin film, and a pigment suspended therein.

The paper thus prepared is placed in a light-tight envelope before exposure and may then be mailed or otherwise transmitted to its destination. If the paper is folded with the sensitive face innermost, the folding will assist in protection against light. The envelope may be made light-tight by a black lining or by coloring the inside black or some other protective color.

When the recipient opens the envelope and removes the sheet of paper, if the paper carries any indicia in ink of the final color, he will be confronted at once with the message carried by that set of indicia. As the paper lies before him, exposed to the light of the

room, the color of the paper background will change from the original toward the final color and the set of indicia printed in the original color will become visible. Simultaneously, the set of indicia printed in the final color will disappear.

Such a paper as that described after being allowed to remain in a well lighted place for five to ten minutes, may, if desired, be immersed in water to fix and render the final coloration permanent. If the pigment ink is one that loses its color after prolonged exposure to light, failure to fix the coloration with water will result in substantially complete obliteration of the indicia after a few weeks.

In preparing the paper in the first instance, an additional design or set of indicia may be embodied in the sensitizing itself as follows:

The paper is first treated with a relatively weak solution and then dried. The desired design or set of indicia may now be printed on the face of the dry paper using, for example, a volatile oil not soluble in water. After this printing the paper is treated a second time with a sensitizing solution. The second solution may be largely prevented from impregnating the areas printed with the volatile oil. In drying after the second treatment, a good circulation of air will evaporate the volatile oil. This product may then be printed with pigment inks as indicated above.

When this paper reaches its destination the results will be like those in the instance already described, except that the design in the paper will appear like a more or less conspicuous water-mark in the background of the final color.

Thus, a circular might present the reader with a brief message in blue, on an almost white background. By the time this message had been read, it would become progressively more or less obliterated, and a second message in white on a blue background would progressively appear. As the second message becomes more and more distinct, the marking in the background will also become noticeable.

Since paper can be prepared to change

color at various speeds, as by varying the content of uranium nitrate, the speed with which different portions of the paper sheet will respond to exposure may be varied. By this means the speed with which the reader will peruse the message may be controlled to concentrate attention on various portions of the message, or merely to require thorough perusal of all of it, or both, and this varying sensitivity may be employed either as a continuous or a discontinuous step-by-step variation.

It is not essential that all the novel features of the invention be employed in conjunction, as they may advantageously be utilized in various combinations and sub-combinations.

What we claim is:—

1. A piece of printed matter having an area covered with ink, another area sensitive to light to develop a change of color at a predetermined speed and to a predetermined final tint, and a third area sensitive to light to develop a change of color at a predetermined speed and to a predetermined final tint, the speed and the final tint for the third area being different from the speed and final tint for the second area, said first area overlying portions of said second and third areas, the ink covering said first area being of fugitive color and becoming transparent after prolonged exposure to light.

2. A piece of printed matter having an area covered with ink, a second area sensitive to light to develop a change of color at a predetermined speed and to a predetermined final tint, and a third area sensitive to light to develop a change of color at a predetermined speed and to a predetermined final tint, the speed and the final tint for the third area being different from the speed and final tint for the second area, said first area overlying portions of said second and third areas.

3. A piece of printed matter having an area covered with ink, a second area sensitive to light to develop a change of color at a predetermined speed and to a predetermined final tint, and a third area covered with ink, the color of said first area being substantially identical with the undeveloped color of the second area, and the color of said third area being substantially identical with the developed color of the second area.

4. A piece of printed matter having an area covered with ink, a second area sensitive to light to develop a change of color, the covered area being substantially identical in color with the original unexposed color of said second area.

5. A sheet of material having an area of permanent color, and a second area sensitive to light to develop a change of color, the color of said first area being substantially identical with the original unexposed color of said second area.

6. A piece of printed matter having an

area covered with ink, a second area sensitive to light to develop a change of color at a predetermined speed and to a predetermined final tint, and a third area sensitive to light to develop a change of color at another predetermined speed and to the same predetermined final tint.

7. A sheet of material having an area of permanent color, a second area sensitive to light to develop a change of color, and a third area of permanent color, said second area being substantially identical in color with said first area before exposure and with said third area after exposure.

8. A piece of printed matter having an area of permanent color, a second area sensitive to light to develop a change of color to a predetermined final tint, and a third area sensitive to light to develop a change of color to a predetermined final tint, the final tint for the third area being different from the final tint for the second area, the color of said first area being substantially identical with the initial unexposed color of said second and third areas.

9. A piece of printed matter comprising a sheet impregnated with chemicals so as to change color upon exposure to light, and indicia printed on said sheet in pigment ink of a color identical with the original color of the sheet, different portions of said sheet having different sensitivities so as to develop at different speeds, said sheet being susceptible of intensification and fixing of its color by immersion in water.

10. A piece of printed matter comprising a sheet impregnated with chemicals so as to change color upon exposure to light, and indicia printed on said sheet in pigment ink of a color identical with the original color of the sheet, said sheet being susceptible of intensification and fixing of its color by immersion in water.

11. A piece of printed matter comprising a sheet impregnated with chemicals so as to change color upon exposure to light, and indicia printed on said sheet in pigment ink of a color identical with the original color of the sheet.

12. A piece of printed matter comprising a sheet impregnated with chemicals so as to change color upon exposure to light, and indicia printed on said sheet in pigment ink of a color identical with one of the colors taken by the sheet itself during exposure.

13. A piece of printed matter comprising a sheet impregnated with chemicals so as to change color upon exposure to light, and indicia printed on said sheet in a color identical with the original color of the sheet.

14. A sheet having a light-sensitive surface to change color upon exposure to light and bearing indicia of a permanent color similar to the original color of said surface.

15. A sheet having a light-sensitive sur-

face to change color upon exposure to light and bearing indicia of a permanent color similar to the original color of said surface and also bearing indicia of a color different from said original color.

5 16. A sheet having a light-sensitive surface to change color upon exposure to light and having indicia printed on said surface in ink of a color not contrasting with the original color of said surface but which will contrast with the final color thereof.

10 17. A sheet having a light-sensitive surface to change color upon exposure to light and having indicia printed on said surface in ink of a color not contrasting with the original color of said surface but which will contrast with the final color thereof, and also having printed on said surface indicia in ink of a color different from the original 15 color.

20 In testimony whereof, I have signed my name to this specification.

ALBERT B. DEWEY, JR.

25 In testimony whereof, I have signed my name to this specification.

NICHOLAS D. CHERONIS.
